(57) CLAIM

The ornamental design for refrigerator door handle, as shown and described.

DESCRIPTION

FIG. 1 is a perspective view of a handle for a refrigerator door according to the present invention.

FIG. 2 is a front view of the handle.

FIG. 3 is a top view of the handle.

FIG. 4 is a bottom view of the handle.

FIG. 5 is a view from one end of the handle, with the view from the opposite end being the same; and,

FIG. 6 is a front elevation view of a refrigerator having the handle of the present invention mounted on the refrigerator door.

The broken lines are for illustrative purposes only and form no part of the claimed design.
